UNITED STATES PATENT OFFICE.

ARTHUR C. SOULE, OF SAN FRANCISCO, CALIFORNIA.

FABRICATED WINDOW-SASH MOUNTING.

1,356,095.

Specification of Letters Patent. Patented Oct. 19, 1920.

Application filed August 9, 1918. Serial No. 249,053.

To all whom it may concern:

Be it known that I, ARTHUR C. SOULE, a citizen of the United States, and a resident of the city and county of San Francisco, State of California, have made a new and useful Invention—to wit, Fabricated Window-Sash Mountings; and I do hereby declare the following to be a full, clear, concise, and exact description of the same.

10 The invention relates particularly to the construction, arrangement and manner of installing the mounting, and to means for controlling the operation of the sashes therein.

15 Among the objects of the invention are to produce a structure of this nature capable of being fabricated in quantities and installed within window casings or frames with the minimum amount of labor and expense, and to provide a sash control of superior merit for the purpose.

20 In this specification and the annexed drawings the invention is illustrated in the form considered to be the best, but it is to be understood that the invention is not limited to such form, because it may be embodied in other forms, and it is also to be understood that in and by the claims following the description, it is desired to cover the invention 25 in whatever form it may be embodied.

In the accompanying one sheet of drawings,

30 Figure 1 is a perspective view from the inside of a window frame partially broken away and shown in cross section, illustrating the construction and arrangement of the sash installation.

35 Fig. 2 is an enlarged detail of a window frame shown in cross section, having a single sash mounted therein in accordance with this invention.

40 Fig. 3 is a fragmentary detail in side elevation illustrating the pivotal and frictional connection of the support arm with the side 45 of the sash.

Fig. 4 is a similar view illustrating the connection of the support arms with the window frame.

50 Fig. 5 is a similar view in front elevation illustrating the resilient pivotal connection of the sash with the sash guides.

55 Fig. 6 is a similar view of the same in plan taken from above in cross section on the line VI—VI, Fig. 5.

In detail the construction illustrated in the drawings includes the conventional window frame composed of the sill 1, the stool 2, the side jambs 3—3 and the lintel 4, joined in the usual manner to form a rectangular frame or casement.

60 By the present construction and invention the sashes and their mountings may be fabricated in quantities and easily installed by mechanics of ordinary skill, with the insurance of perfect operation. This is accomplished by providing the substantially

65 L shaped fixture strips 5 having the angular extensions 6 thereon. To these strips are rigidly fixed longitudinally as a part thereof of the sash guides 7, preferably consisting of a length of flat metal with rounded edges, provided with a suitable weather resisting coating. The strips 5 are suitably grooved at the lateral edges of the guides 7, to clear the curled edges 8 of the sliding pivotal 70 shoes 9 slidably engaging the guides 7. The stiles 10—10 of the sash are provided with spring tension members 11, fixed thereto on opposite sides of the upper corners and terminating with the ends 13 parallel with the 75 sash stiles, at which point they are pivoted at 14 to the pivot shoes 9. The tension of these spring members at 12 is inward toward the sash so as to pull the strips 5 and sash snugly together at the contacting edges 85 14', see Fig. 6. Both the upper and lower sashes, if more than one is used, are similarly pivoted at their upper corners, and slidably engage the guide strips 7.

80 The angular extensions 6 of the strips 5 act as stops for the abutment of the inner face of the sash stiles 10. For the purpose of further weather-proofing the joints between the sashes and their mountings I provide metal weather strips 15 having angular 85

90 bent back edges 16 to engage a similarly shaped groove in the inner face of the extension 6. The angular edges 16 co-operating with the tapered grooves in the strips 95 tend to pull the strips 5 snugly against the edges of the sash contributing to the tightness of the joints at 14' as well as at 17, insuring a close, tight, weatherproof fit between the sash and the strips 5 at all points of contact. These grooves are substantially 100 V shape to facilitate entrance of the edges 16 thereinto.

105 The weight of the sashes is supported by

the support arms 18 pivoted to the sash stiles 10 at or near their centers on the fixed pivots 19; the opposite ends of the arm 18 are pivoted at 20 to sliding shoes 21, similar in construction to the pivot shoes 9 and similarly engaging the guide strips 7. The pivots 20 may be fixedly instead of slidably connected to the guides 7 at the proper point and under normal circumstances the manipulation of the sash on its pivots 14 can be properly adjusted, but such a simple mounting has proven unreliable in control of the device under influence of strong wind or other conditions likely to change its set position. For that reason I prefer to interpose the sliding shoes 21 which permits the pivot 20 to move vertically in conformity with the control link 22 fixedly pivoted at 23 to the guide 7 and to the support arms 18 at 24, transforming the arm 18 from a simple lever to a compound lever by moving the fulcrum of the point 20 to the point 24, the multiplied leverage giving a better control over the operation of the sash through the support arms 18 as hereinafter will be described.

To control the operation of the sash on the support arms 18, I interpose the friction links 25 pivoted at 26 to the sash at a point spaced from the support pivot 19, the opposite end of the links being pivoted at 27 to the friction slides 28 having their edges crimped around the edges of the support arm 18 and adapted to frictionally slide upon the same.

For greater rigidity of the structure and to insure the proper spacing of the pivotal points 19 and 26 I prefer to interpose the plates 30 fixed to the sash stiles by the screws 31, behind the rabbet edges 32 that inclose the support arms 18, the links 22 and 25 and assembled mechanism, so that they are hidden when the sashes are closed.

Thus assembled a multiplicity of sashes may be combined within a single mounting fabricated and assembled ready to be forwarded to the point of installation with their working parts in their proper relative positions and adjustment. It is usual to leave the lower end of the strips 5 a little longer than specified, so that they may be sawed off and shaped to fit the top surface of the sill 1 as at 33. If exact specifications are available at the mill even this part of the operation may be performed at the point of fabrication. The sashes and the assembled mountings are installed within the frame or casement described, by resting the lower ends of the fixture strips 5 on the sill 1 and swinging their tops against the stop 34 on the lintel between the side jambs 3-3. To facilitate lateral fitting I leave the raised beads 35 on the outer surfaces of the strips 5 which may be

easily planed down to accomplish the approximate fit between the mounting and the jambs 3-3. Thus inserted within the frame the stops 36 and 37 are nailed to the interior of the window frame. Thus the installation of the sashes and their mountings is complete, and held in permanent assembly with the casement frame between the stops 34, 34', 36 and 37. The beads 35 are trimmed down sufficiently to allow the necessary play to compensate for expansion and contraction of the structure due to weather changes, at all times allowing free operation of the moving parts.

Sashes thus mounted operate substantially as follows: The meeting rails 38-39 are suitably shaped, in the usual manner, to exclude weather and to rest one within the other so that when the sashes are closed they present an even plane, or if it is desired the guide strips 7 may be offset on the strip 5 so as to permit the sashes to overlap at the meeting rails. This, however, introduces complications and is not the preferred form. With the sashes thus assembled and installed and presumed to be in the fully closed position and it is desired to open them, the first action is to push outward on the lower rail 40 of the lower sash. This permits the sash to swing outward on its pivots 14 causing the pivotal shoes 9 to slide downward on the guides 7, releasing the meeting rail 39 from the meeting rail 38, the sash assuming any angle desired by the operator. In similar manner the top sash can also be placed at any angle desired. The pivot shoes 9 descend as the angle of the sash approaches the horizontal, at which point continued action accomplishes the total reversal of the sash, presenting its outer surface to the interior of the room to facilitate washing. The lower pivot 20 of the support arm 18 rises under the influence of the fulcrum 24 as the sash opens. The link control 22 performs a valuable function in controlling the sash, as it transforms what would be a simple pivotal action at the point 20, into a sliding action accommodated by the shoe 21, and causes a pinching or jamming action which must be overcome before the sash can move. To further insure the maintenance of the desired angle of the sash, I interpose the links 25 with the friction slides 28, interposing the same action introduced by the links 22, tending to pinch or jam, and together with the friction exerted by the shoes 28, holding the sash in any set position, yet capable of easy movement at the will of the operator handling the sash near the bottom rail 40. The link 25 is preferably pivoted at 26 below the pivot 19 for the reason that the more nearly this link 25 approaches the horizontal angle, the more counter leverage it exerts, to prevent the displacement of the sash from its set position.

The same is true of the link 22 which may be made much longer, but the lengthening of which increases the rise and fall of the plate 21 proportionately interferes with reversal movement of the sash and is found to be needless particularly in combination with the link 25 and its assembled parts.

If each sash is assembled in its separate fixtures as shown in Fig. 2, any number may be assembled in a single casement frame. The duplex assembly of two sashes assembled between two double fixture strips 5, as in Fig. 1, illustrates the adaptability of the system. Neither do I wish to be understood as limiting this invention to the specific form of sash control, as many forms covered by patents in my name and others may be interposed between the sashes and the fixture strips.

In adapting this invention to steel construction and to meet other special conditions, modifications within the purview of the invention are available to those skilled in the art in practising the invention.

Having thus described my invention, what I claim and desire to secure by Letters Patent is:

1. A window sash mounting including a frame; fixture strips engaging said frame and having guides thereon; a sash slidably pivoted to said guides; support arms pivoted to said sash and slidably pivoted to said guides; control links pivoted to said strips and said arms.

2. A window mounting comprising fixture strips mounted in a window frame and capable of lateral movement relative to each other; a sash; sash guides attached to said strips; pivoted shoes slidably engaging said guides; and resilient members attached to said sash and to said shoes and adapted to draw said sash and strips tightly together.

3. A window mounting comprising fixture strips having stops thereon and mounted in a window frame and capable of lateral movement relative to each other; sash guides attached to said strips; pivoted shoes slidably engaging said guides; a sash; and resilient members attached to said sash and

said shoes, adapted to draw said sash and strips in tight contact with each other.

4. A window mounting comprising a window frame having a sash therein; fixture strips adapted to move toward or from each other interposed between said sash and frame; sash guides attached to said strips; pivoted shoes slidably engaging said guides and resilient members attached to said sash and shoes and adapted to move said sash and strips either toward or from each other.

5. A window mounting comprising fixture strips adapted to move toward or from each other mounted in a window frame; a sash; sash guides attached to said strips; pivoted shoes slidably engaging said guides and resilient members attached to said sash and to said shoes and adapted to move strips laterally either to or from each other.

6. A window mounting comprising a window frame having a sash therein; fixture strips having stops thereon interposed between said sash and frame and capable of lateral movement either toward or from said sash; sash guides attached to said strips; pivoted shoes slidably engaging said guides and resilient members attached to said sash and shoes adapted to draw said sash and strips into contacting relationship.

7. A window mounting comprising a window frame having a sash therein; fixture strips adapted to move toward or from each other interposed between said sash and frame, and having longitudinal depressions therein; sash guides mounted within the depressions of said strips; pivoted shoes slidably engaging said guides and substantially flush with the outer edge of said sash guides and resilient members attached to said sash and shoes adapted to draw said sash and strips tightly together.

In testimony whereof, I have hereunto set my hand at San Francisco, California, this 27th day of July, 1918.

ARTHUR C. SOULE.

In presence of—

A. J. HENRY,
BALDWIN VALE.
